CLAIM

The ornamental design for a textured spa basin, as shown and described.

DESCRIPTION

Applicant has a related application pending, 29/340,028 filed Jul. 13, 2009.

FIG. 1 is a top front perspective view of the textured spa basin.

FIG. 2 is a bottom rear perspective view thereof;

FIG. 3 is a right side elevation view thereof;

FIG. 4 is a front elevation view thereof;

FIG. 5 is a left side elevation view thereof;

FIG. 6 is a rear elevation view thereof;

FIG. 7 is a top plan view thereof; and,

FIG. 8 is a bottom plan view thereof.

The broken lines showing a drain in FIGS. 2, 7 and 8 depict environmental subject matter only and form no part of the claimed design.
